UNITED STATES PATENT OFFICE.

WEBB L. GIBBS, OF CHICAGO, ILLINOIS.

LOCOMOTIVE-JOURNAL-BOX-LUBRICATING APPARATUS.

Application filed October 30, 1925. Serial No. 65,773.

My invention relates to improvements in locomotive journal box lubricating apparatus.

The principal object of my invention is to provide an improved perforated plate whereby the waste of grease or lubricant is reduced to a minimum.

Another object is to provide improved plates which will retain their shape longer than will the plates at present in common use.

Other objects relate to features of construction and arrangement of parts, which will become apparent from a consideration of the following specification and accompanying drawings, wherein—

Figure 1 is a convenient driving box showing one form of my perforated plate therein.

Fig. 2 is a longitudinal sectional view taken on line 2—2, Fig. 1.

Fig. 3 is a perspective view of another form of my invention, and

Fig. 4 is a view showing the relation of the locomotive axle to the plate illustrated in Fig. 3.

In locomotives of common type, the driving boxes are supplied with lubricant, usually in the form of cakes of grease, moulded to suitable shape and size, which cakes are gradually fed to the friction surfaces of the axles through foraminous plates by means of spring actuated followers. A foraminous plate, of the type referred to, is usually constructed of sheet metal, such as steel, and has an upper surface curved to closely contact with the lower portion of the axle. Rotation of the axle in one direction more than in the other causes the plate to become somewhat deformed, which in time renders the same unsuitable for further service.

The plate has vertical side extensions which extend downwardly one-half the depth of the cellar, and in the space between the upper portion of the sides and the curved portion of the plate the grease often burns or carbonizes, rendering the same unfit for use. This grease which thus is wasted must be removed, and the plate cleaned before fresh lubricant is supplied. These defects cause considerable waste, both

in materials and in time involved in correcting them, and it is to a remedy of these defects that my invention is directed. 55

In the drawings, 10 is a conventional driving box having a brass or bearing 11, which rests upon the locomotive driving axle 12. Suitably supported in the lower portion of box 10 is the cellar 13, which is usually formed of cast iron. A follower plate 14 in the cellar 13 is urged upwardly by a spring 15 and maintains a cake of grease 16 against the lower surface of the perforated or foraminous plate, indicated, 65 generally, by numeral 17 in Figs. 1 and 2. This plate 17 is usually formed of sheet metal and has a perforated curved portion 17^a which contacts with the axle 12, a pair of vertical extensions or side members 17^b 70 which extend downwardly to approximately one-half the depth of the cellar 13, and end flanges 17^c which assist in retaining the lubricant in position. The axle in turning carries grease from the perforations in the 75 plate 17, as will be clear. The follower 13 is urged upwardly with sufficient force only to maintain the grease in contact with the curved portion 17^a of the plate 17. A pair of eye bolts 18 projects from the follower 80 13 and constitute means for retracting the follower when fresh lubricant is to be supplied, and also indicate by their exposed portions the amount of the unconsumed grease. 85

The form of the plate 17, shown in Figs. 1 and 2, corresponds to the present day conventional plate. I have shown, however, filler members 19 in the spaces formed between the upper portions of the sides 17^b 90 and the perforated portion 17^a of the plate 17. It is in these spaces that the grease burns or carbonizes in use, resulting in considerable waste where the present type of plates is used. The fillers 19 may be of 95 wood, secured in position by any suitable fastening means. The fillers 19 prevent the grease from entering the upper spaces of the plate, as will be seen, and also render the plate as a whole more rigid, thus preventing the reduction in the angle between the portion 17^a at one side with the adjacent vertical portion 17^b and the corresponding displacement of the portions on the other 100

side of member 17, which is caused by the rotation of the axle largely in one direction.

End plates, of conventional form, but not shown here, are pivoted, as at 20, to the box 10 to prevent entrance of dust, etc., into the driving box.

A modified form of my invention is shown in Fig. 3, and comprises a plate, indicated, generally, by numeral 21, having vertical sides 21^a, curved perforated portion 21^b and inclined walls 21^c. The usual end flanges 21^d are also provided. The inclined walls 21^c may be formed integrally with side walls 21^a and have their upper edges welded or otherwise secured to the lower surface of portion 21^b.

Fig. 4 is a diagrammatic representation of a locomotive axle 22 and my plate 21 showing their relation when in a driving box (not shown), such as that previously described. It will be seen that the inclined walls 21^c function similarly to the fillers 19 of the previously described form, in that they render the plate rigid and tend to direct the grease adjacent the side walls obliquely toward the perforated portion of the plate, and eliminate the space found in the present day types of plates in which the grease collects and becomes unfit for use.

Both forms of my invention herein shown and described are adapted for use in a standard journal box without modification thereof.

Although I have shown certain forms of my improvements for the purpose of illustration, it will be seen that modifications

may be made therein without departing from the spirit of my invention, and I do not wish to be restricted to the forms shown except as limited thereto by the appended claims.

What I claim is:

1. A grease plate having a pair of vertical side members, a curved foraminous section, and inclined walls extending from said vertical walls to said curved portion. 45

2. A grease plate having a pair of vertical side members, a curved foraminous section, and inclined walls integral with said side members and said foraminous section. 50

3. An article of the class described comprising a curved foraminous portion, and a pair of vertical side walls terminating in inclined members extending inwardly and upwardly into contact with the lower surface of said foraminous portion. 55

4. An article of the class described, comprising a pair of side walls, a curved foraminous portion, and inclined means between said walls and section secured to and adapted to brace the same against deformation. 60

5. An article of the class described comprising a curved plate having lateral imperforate sections and an intermediate foraminous section, and relatively stationary inclined means below said imperforate sections for deflecting upwardly moving lubricant away from said imperforate sections 70 and toward said foraminous section. 65

In testimony whereof, I have subscribed my name.

WEBB L. GIBBS.
